TOY GUN

Meredith Arthur Reed, Fort Wayne, Ind., assignor
to The Kitchen Maid Corporation, Andrews,
Ind., a corporation of Indiana

Application December 16, 1933, Serial No. 702,774

16 Claims. (Cl. 124—14)

This invention is a novel improvement in band projecting guns or pistols adapted to aerially project a rubber band, or a plurality of rubber bands in succession as the trigger is successively actuated, the rubber bands being stretched between the outer end of the gun barrel and between notches in the edge of the barrel adjacent its inner end, a braid underlying the ends of the bands in the notches for releasing the bands as the braid is pulled.

The principal object of the invention is to provide in such toy guns novel trigger means for actuating the braid to release a rubber band with each actuation of the trigger, said trigger means releasing the first rubber band in a positive manner, and each subsequent band being released in an equally positive manner due to the construction in which the braid is pulled just far enough on each actuation of the trigger to release one band; and said braid having an elastic section therein maintaining the braid taut at all times, and taking up the slack which would be produced therein due to the increments of increase in the length of the braid resulting from release of successive bands. Upon release of the trigger after each actuation the elastic section of the braid returns the trigger to normal position ready for a new discharge, and at the same time the slack is taken up in the braid. Upon the next actuation of the trigger the braid is automatically pulled just far enough to release the next band regardless of the number of "loads" still discharged.

My novel arrangement of braid and trigger makes it possible to hold the toy gun, aim it, and discharge it with one hand, like an actual gun or pistol. Heretofore toy guns have been made utilizing the above notch and braid arrangement, but the guns had no trigger means and had to be held in one hand while the braid was pulled by the other hand, and hence did not sufficiently resemble actual guns to be acceptable; but my novel trigger means obviates the above defect and fulfills all requirements in this respect.

I will explain the invention with reference to the accompanying drawing which illustrates several practical embodiments thereof to enable others to adopt and use the same; and I will summarize in the claims the novel features of construction, and novel combinations of parts, for which protection is desired.

In said drawing:—

Fig. 1 is a side elevation of one form of my band projecting gun; showing a plurality of rubber bands mounted thereon ready to be projected

in succession by successive operations of the trigger.

Fig. 2 is a view similar to Fig. 1 with the stock partly broken away, showing in full lines the slide in normal position; and in dotted lines the slide retracted to actuate the band releasing braid. 5

Fig. 3 is a view similar to Fig. 2 showing the braid released for loading.

Fig. 4 is a section on the line 4—4, Fig. 2.

Fig. 5 is a side elevation partly broken away 10 showing a modified form of gun and trigger arrangement.

Fig. 6 is a side elevation showing a still further modified form of gun and trigger arrangement.

My band projecting gun or pistol, shown in 15 Figs. 1 to 4, comprises a barrel simulating member 1 of wood or other suitable material extending the full length of the gun, and provided with a series of slightly undercut notches 1a in its upper edge, six such notches being shown although any desired number may be used. Barrel 1 is preferably provided with an upper notch 1b and a lower notch 1c in its outer end for the purpose hereinafter explained. 20

Barrel 1 is fixedly secured in the upper portion 25 of a U-shaped member 2 forming the stock of the gun; and a reciprocable slide 3 is mounted in the base of the stock 2 below the barrel 1, said slide being operated by a trigger 4 depending from the underside of the slide and extending through an elongated slot 2a in the bottom of the stock 2, whereby as the trigger is drawn rearwardly by the forefinger slide 3 will also be shifted rearwardly into the position shown in dotted lines in Fig. 2. 30

Depending from the stock 2 in rear of trigger 4 is a handle or butt member 5. If desired, slot 2a may be elongated sufficiently to receive a tenon 5a on the upper end of the handle 5. The parts 1, 2 and 5 are preferably held in proper 35 relation by means of tacks or screws 6, as shown in Fig. 4.

A braid 7 is secured by tack 1a to the upper edge of barrel 1 slightly in advance of the outermost notch 1a, and extends rearwardly overlying 45 the upper edge of the barrel, and under a guide 1b, and around the rear end of barrel 1, and through the U-shaped stock 2 below slide 3. An elastic or other extensible band 8 is secured to the outer end of braid 7 beyond the stock 2, which 50 extensible band 8 is adapted to be conveniently hooked in the lower notch 1c at the outer end of barrel 1 as shown in Fig. 1. Instead of using a band 8 the braid 7 may have an extensible section formed therein, and the outer end of the braid 55

may be fixed to the barrel or stock instead of being hooked over the outer end of the barrel. Braid 7 forms the releasing means for the ends of the rubber bands R in notches 1a, said bands being stretched between the upper notch 1b at the outer end of barrel 1 and the notches 1a, with the braid 7 underlying the ends of the bands R in the notches and conforming with the contour of the notches, whereby as braid 7 is pulled rearwardly the inner ends of the bands R will be raised out of their respective notches by the braid, the bands R being released in succession as trigger 4 is successively actuated.

The pulling of the braid 7 is effected by the trigger 4 which actuates the slide 3, the inner end of the slide when retracted stretching the braid beyond the rear end of the barrel as shown in Figs. 2 and 3. Since braid 7 is maintained taut by the extensible member 8 (when the latter is hooked in notch 1c) the braid will normally yieldably maintain the slide 3 so that its inner end is substantially flush with the inner end of barrel 1 as in full lines in Fig. 2. Although there is no positive connection between slide 3 and braid 7, nevertheless when slide 3 is shifted rearwardly as shown in dotted lines in Fig. 2, the band 8 will necessarily yield and friction will be set up between braid 7 and slide 3 at the bottom and rear end of the slide, which friction will be sufficient to pull the portion of the braid, which overlies the upper edge of barrel 1, enough to lift the end of the rearmost band R out of its notch 1a and thereby positively discharge such band. When the trigger 4 is released, slide 3 will again assume its normal position, and the increase in length of braid 7 caused by the release of the band, will be taken up by the elasticity of member 8 so that each successive band R will be similarly positively released.

By the above construction, the braid 7 used to release the bands R is at all times kept taut by the expandable member 8; and the slide 3 when pulled back by the trigger 4 contacts with braid 7 around the breech of the gun while it is held taut under the tension of member 8. This tension holds the braid 7 along the bottom of the slide 3 and against the rear end of the slide 3, so that braid 7 is pulled just far enough and hard enough when retracted to positively release one band R. Upon releasing the trigger 4 the expandable member 8 immediately pulls slide 3 back into place ready for another discharge. At the same time the slack is taken up in braid 7 so that, on the next pull of the trigger 4, the slide 3 contacts the braid at the breech of the gun in exactly the same way and positively releases the next load. Each load is discharged in the same way and each time the expandable member serves to take up the slack, and the slide operates to release only one band.

In order to load the gun, it is necessary to first unhook extensible member 8 from notch 1c so as to remove the tension from braid 7. The braid need not be pulled through the stock to produce the slack therein but the trigger action may be depended upon to do this. The gun may then be held in the left hand with the forefinger on the trigger. With braid 7 disposed directly over notches 1a the first rubber R is held stretched over the first and second finger, and looped into the notch 1b at the outer end of barrel 1. The band R is then pulled back slowly, and with the fingers of the right hand is pressed down into the outermost notch 1a overlying the

braid 7 which readily conforms with the shape of the notch. The remaining bands R are loaded in the other notches similarly, and the extensible member 8 is again hooked into notch 1c at the end of barrel 1. The gun is then ready for shooting, and in the embodiment shown in the drawing will shoot six times without reloading.

In Fig. 5 a modification is shown in which the barrel 1 is provided with the notches 1a and the braid 7, as in Figs. 1-4. A pulley 10 is mounted in the stock 2 behind the barrel and around the pulley 10 extends the braid 7, the braid continuing forwardly below the barrel in the manner similar to that shown in Figs. 1-4. The underside of the barrel 1 is provided with a recess 1x into which an offset portion 11a of a pivoted trigger 11 projects when the trigger is actuated, the braid being pulled by the offset portion 11a deflecting same into recess 1x, producing a result the same as that described with reference to slide 3 of Figs. 1 to 4.

In Fig. 6 a further modification is shown in which the recess 1y for the offset portion 12a of the trigger 12 is formed in the inner end of barrel 1 rather than in the underside as in Fig. 5; but the braid 7 will be pulled in the same manner as that described with respect to Fig. 5, when trigger 12 is actuated, the entry of the offset portion 12a of the trigger in the recess 1y causing the braid to stretch and release the band R.

I claim:

1. In a band projecting gun, a stock; a barrel simulating member mounted thereon having a notch adapted to receive the end of an elastic band stretched between the outer end of the barrel and the notch; a braid adapted to underlie the end of the band in the notch, a return bend guide for the braid in rear of the notch; said braid extending rearwardly around the guide and extending forwardly and secured to the gun; the braid beyond the guide having an elastic portion for maintaining the braid taut; and trigger means in the stock adapted to engage the braid and pull same sufficiently to release the band upon actuation of the trigger.

2. In a gun as set forth in claim 1, a slide interposed between the barrel and braid and in normal position extending to a point adjacent the return guide, said slide being operated by the trigger, whereby when the trigger is actuated the slide will be shifted rearwardly beyond the guide and thereby pull the braid.

3. In a gun as set forth in claim 1, said barrel having a recess in its rear end; and said trigger having an offset portion adapted to deflect the braid into the recess when the trigger is actuated and thereby pull the braid.

4. In a gun as set forth in claim 1, said barrel having a recess in its lower edge; and said trigger having an offset portion adapted to deflect the braid into the recess when the trigger is actuated and thereby pull the braid.

5. In a band projecting gun, a stock; a barrel simulating member mounted thereon having a series of notches in one edge adapted to receive a series of elastic bands stretched between the outer end of the barrel and the notches respectively; a braid secured to the barrel and adapted to underlie the ends of the bands in the notches, a return bend guide for the braid in rear of the notches; said braid extending rearwardly around the guide and extending forwardly through the stock and secured to the gun, the braid beyond the guide having an elastic portion for maintaining the braid taut; and trigger means in the

- stock adapted to frictionally engage the braid and pull same sufficiently to positively release the bands in succession as the trigger is successively actuated, the extensible member taking up the slack in the braid upon the release of each band. 5
6. In a gun as set forth in claim 5, a slide interposed between the barrel and braid and in normal position extending to a point adjacent the guide, said slide being operated by the trigger, whereby each time the trigger is actuated the slide will be shifted rearwardly beyond the 10 guide and thereby pull the braid sufficiently to discharge one band.
7. In a toy gun as set forth in claim 5, said barrel having a recess in its rear end; and said trigger being pivoted in the stock and having an offset portion adapted to deflect the braid into the recess when the trigger is actuated and thereby pull the braid. 15
8. In a toy gun as set forth in claim 5, said barrel having a recess in its lower edge; and said trigger being pivoted in the stock and having an offset portion adapted to deflect the braid into the recess when the trigger is actuated and thereby pull the braid. 20
9. In a band projecting gun, a stock; a barrel simulating member mounted thereon having a series of notches in its upper edge adapted to receive a series of elastic bands stretched between the outer end of the barrel member and the notches respectively; a braid secured to the barrel adapted to underlie the ends of the bands in the notches, said braid extending rearwardly around the inner end of the barrel and forwardly through the stock and extending towards the outer end of the barrel; an extensible member secured to the outer end of the braid and hooked over the outer end of the barrel to maintain the braid taut; and trigger means in the stock adapted to frictionally engage the braid and pull same sufficiently to positively release the elastic bands in succession as the trigger is successively actuated, the extensible member taking up the slack in the braid upon the release of each band. 25
10. In a gun as set forth in claim 9, said stock being U-shaped in cross-section; a slide in the stock interposed between the barrel and braid and extending to a point adjacent the rear end of the barrel, said slide being operated by the trigger, whereby each time the trigger is actuated the slide will be shifted rearwardly beyond the barrel and thereby pull the braid sufficiently to discharge one band. 30
11. In a gun as set forth in claim 9, said barrel terminating with the stock and having a recess in its rear end; and said trigger being pivoted in the stock and having an offset portion adapted to deflect the braid into the recess when the trigger is actuated and thereby pull the braid. 35
12. In a gun as set forth in claim 9, said barrel terminating within the stock; a guide pulley journaled in the stock in rear of the barrel around which the braid passes; said barrel having a recess in its lower edge; and said trigger being pivoted in the stock and having an offset portion adapted to deflect the braid into the recess when the trigger is actuated and thereby pull the braid. 40
13. In a band projecting gun, a stock; a barrel simulating member mounted thereon having a series of notches in its upper edge adjacent its rear end adapted to receive a series of elastic bands stretched between the outer end of the barrel member and the notches respectively; a braid secured to the barrel adapted to underlie the ends of the bands in the notches, said braid extending rearwardly around the inner end of the barrel and forwardly through the stock and extending towards the outer end of the barrel; an extensible member secured to the outer end of the braid and hooked over the outer end of the barrel to maintain the braid taut; and trigger means in the stock adapted to frictionally engage the braid and pull same sufficiently to positively release the elastic bands in succession as the trigger is successively actuated, the extensible member taking up the slack in the braid upon the release of each band. 45
14. In a gun as set forth in claim 13, said stock being U-shaped in cross-section; a slide in the stock interposed between the barrel and braid and extending to a point adjacent the rear end of the barrel, said slide being operated by the trigger, whereby each time the trigger is actuated the slide will be shifted rearwardly beyond the barrel and thereby pull the braid sufficiently to discharge one band. 50
15. In a gun as set forth in claim 13, said barrel terminating with the stock and having a recess in its rear end; and said trigger being pivoted in the stock and having an offset portion adapted to deflect the braid into the recess when the trigger is actuated and thereby pull the braid. 55
16. In a gun as set forth in claim 13, said barrel terminating within the stock; a guide pulley journaled in the stock in rear of the barrel around which the braid passes; said barrel having a recess in its lower edge; and said trigger being pivoted in the stock and having an offset portion adapted to deflect the braid into the recess when the trigger is actuated and thereby pull the braid sufficiently to discharge one band. 55
